UNITED STATES PATENT OFFICE.

DANIEL EDWARD WATERS, OF ST. PAUL, MINNESOTA.

DISPLAY SIGN.

Application filed October 17, 1922. Serial No. 595,189.

To all whom it may concern:

Be it known that I, DANIEL EDWARD WATERS, a subject of the King of Great Britain, residing in the city of St. Paul, in the State of Minnesota, United States of America, have invented certain new and useful Improvements in Display Signs, of which the following is the specification.

The invention relates to improvements in display signs and an object of the invention is to provide a moving sign which by virtue of its movement will attract the attention of the public, thereby rendering this sign a valuable one for display purposes.

15 A further object of the invention is to provide a sign which can be adapted for out doors and which when once set in operation will continue to work without further attention.

20 A further and more specific object of the invention is to improve and simplify the construction of the sign previously patented by me and as fully shown and described in United States Patent No. 25 1,313,434, dated August 19th, 1919, such improvements giving me the same amount of sign changing with a less number of moving signs and consequently less moving parts.

30 With the above more important objects in view the invention consists essentially in the arrangement and construction of parts hereinafter more particularly described and later pointed out in the appended claims, reference being had to the accompanying drawing in which:

Fig. 1 is a front view of my complete sign board.

Fig. 2 is a horizontal sectional view 40 through the board with parts broken away and the shifter shown in plan view.

In the drawing like characters of reference indicate corresponding parts in the several figures.

45 In the following disclosure I have a plurality of stationary sign boards and one shifting sign board, and as the manner of mounting the moving or shifting sign was fully disclosed in my prior patent I have not considered it necessary to enter into such structural details and accordingly for the purpose of this description, it will be understood that the shifting sign board is suitably mounted, such as in the manner described in 50 such prior patent, or in any other suitable way, which will permit it to slide backward-

ly and forwardly within the sign board frame.

Referring now to the drawing:

1 represents a sign board frame carried 60 by suitable legs 2 and formed from top and bottom beams 3 and 4 closed at the ends by end posts 5 and 6. Centrally and well to the front of the frame I locate a stationary sign board 7 and at the ends of the said sign board I locate vertically disposed border pieces in the form of legs 8 and 9. Directly to the rear of the legs 8 and 9 and spaced therefrom I locate further vertical legs 10 and 11 and these legs and the end posts 5 70 and 6 support stationary rearwardly disposed end signs 12 and 13, the latter signs each having approximately the same exposure area as the forwardly disposed central sign 7. 75

Referring to Figure 2, it will be observed that there is a space or passage reserved between the front and rear signs. In this passage I locate a sign board 14 which is supported in the frame 1 for endwise sliding 80 movement within the frame. The sign board 14 is practically twice the length of the sign board 7 and provides two exposure areas for advertising or similar material. According to this arrangement it will be apparent that 85 when one exposure area of the moving sign is to the rear of the sign board 7 the other exposure area of the said sign board is in front of the sign board 13, or that 12, depending upon whether the moving sign is at 90 the right or left hand end of its travel. In Figure 2 the moving sign is shown as at the right hand end of its travel.

Consequently, the advertising material appearing on the sign boards 12 and 7 and 95 on the right hand end of the moving sign 14 will be exposed. Should the moving sign be shifted to the left hand end the advertising material on the sign boards 7 and 13 and on the left hand end of the 100 sign board 14 will be exposed.

Any suitable means can be provided for alternately shifting the sign board 14 within the frame, such means preferably being arranged so that it is entirely automatic, 105 and such that after it has brought the shifting sign to either end of the frame it will permit the said sign to remain there for a short period prior to reversing and passing to the other end of the frame. 110

In the present disclosure I have shown a device which I term a shifter and which

is indicated generally by the reference numeral 15. The details of this shifter are not herein described as they form the subject matter of a further application. It embodies, however, an electric motor 16, a driving belt 17, alternately driven belts 18, and 19, and a winding drum 20 which is alternately and intermittently driven in opposite directions by the belts 18 and 19. 10 Winding cables 21 and 22 pass from the drum over suitable pulleys and connect with the opposite ends of the shifting sign, one of the cables winding off the drum, whilst the other is winding on. 15 Accordingly, when the shifter is in operation the moving sign will be shifted backwardly and forwardly within the frame to alternately expose the signs thereon and to alternately cover and expose the stationary 20 end signs. Obviously, this arrangement of sign boards gives just as much variation in the sign exposure as the sign shown in my former patent and as I only have one shifting sign the structure is considerably simplified.

What I claim as my invention is:

1. In a display sign, a centrally disposed forwardly positioned stationary sign board, rearwardly disposed stationary end sign 30 boards and a horizontally movable sign board mounted to the rear of the central sign board and in advance of the end sign boards and designed to be projected alternately in front of the end sign boards.

35 2. In a display sign, a forwardly disposed centrally positioned stationary sign board, rearwardly disposed stationary end

sign boards and a horizontally movable sign board associated with the stationary sign boards and of twice the length of the stationary sign boards, said moving sign board being designed to be alternately shifted in a horizontal direction to alternately expose the opposite ends thereof in front of the end sign boards. 40

3. In a display sign, a supporting frame, a central sign board supported by said frame, end sign boards supported by the frame at opposite sides of and slightly to the rear of the central sign board and a shifting sign mounted in the frame for endwise movement in the space reserved between the central and end sign boards, said shifting sign board being twice the length of 45 the stationary sign boards. 50

4. In a display sign, equi-length central and end stationary sign boards, the said central sign board being located in a different vertical plane to that containing the end sign boards, and a movable sign board contained in a vertical plane positioned between the vertical planes containing the central and end signs, said movable sign board being adapted to be shifted endwise 55 to alternately pass the ends thereof from behind the central sign and expose the same alternately in front of the end signs. 60

Signed at Minneapolis, Minnesota, this 9th day of October, 1922.

DANIEL EDWARD WATERS.

In the presence of—

ELIZABETH WATERS,
MINNIE V. QUINN.
